UNITED STATES PATENT OFFICE.

JAMES E. POTTER, OF PROVIDENCE, RHODE ISLAND.

BUTTON.

1,425,131.

Specification of Letters Patent. Patented Aug. 8, 1922.

Application filed February 1, 1922. Serial No. 533,410.

To all whom it may concern:

Be it known that I, JAMES E. POTTER, a citizen of the United States, residing at Providence, in the county of Providence and 5 State of Rhode Island, have invented certain new and useful Improvements in Buttons, of which the following is a specification.

This invention relates to an improved construction of button more particularly for 10 use as a temporary button for holding the collar-band and cuffs of a freshly laundered or new shirt, but the same may be used for any other purpose for which it is adapted.

The object of this invention is to provide 15 a button formed by folding sheet stock to provide a base portion, a shank portion and a head portion, all from a single piece of metal.

With these and other objects in view, the 20 invention consists of certain novel features of construction, as will be more fully described, and particularly pointed out in the appended claim.

In the accompanying drawings:

25 Figure 1 is a perspective view illustrating my improved form of button.

Figure 2 is a view of the strip of a length 30 of sheet stock from which the button is formed and showing the outwardly swaged cup-shaped portions at the ends which when folded together form the head of the button.

Figure 3 is a sectional view on line 3—3 of Figure 2.

Figure 4 shows the strip as partially bent 35 to form my improved construction of button.

It is found in practice very desirable to provide an inexpensive button to serve as a temporary button for holding the bands and cuff portions of freshly laundered or 40 new shirts until used by the wearer, to take the place of the old style clips or wooden buttons or fasteners and to be so shaped that it will well retain the adjacent portions of the shirt until finally removed by the wearer, 45 and the following is a detailed description of one construction of button which will accomplish this purpose:

My improved button is formed from a strip of sheet stock preferably sheet metal, 50 which is cut into length as at 10, and at the opposite ends of this strip the stock is swaged from the inner face of the strip outwardly into cup-shape as at 11 providing halves of a head having substantially square shoulders

12 on the under side thereof and tapering 55 from the shoulder towards the ends of the stock.

This strip after having been so formed is folded upon itself as at 13 forming a base 14 of a double thickness also forming the 60 shank portion 15 of a double thickness and the enlarged end portions of the shank when brought together cooperate to form a hollow head portion 16 having laterally extending shoulders 12 on its under side and tapering 65 towards its outer end forming a button-head which is somewhat pointed to facilitate passing the head through the buttonholes.

By my improved construction the shank portion of the button is substantially rectangular in cross section having flat side walls whereby the button is prevented from turning in the buttonhole and the shoulders 12 extend laterally from the side faces of the shank to engage the fabric about the button-hole and so effectually prevent the button from dropping out which is the usual fault or trouble with such temporary buttons or holders.

The device is extremely simple and practical and is so inexpensive in construction that it will replace the ordinary wooden button or other fastener now employed for this purpose as my improved button may be constructed from a sheet of sheet stock and 80 folded into finished shape all in a single operation by folding the stock upon itself and owing to its double formation it may be made of extremely thin material and still be of ample strength and stiffness for the 85 purpose required.

The foregoing description is directed solely towards the construction illustrated, but I desire it to be understood that I reserve the privilege of resorting to all the mechanical changes to which the device is susceptible, the invention being defined and limited only by the terms of the appended claim.

I claim:

A button formed of sheet stock folded to 100 provide base and shank portions of double thickness, the free ends of the shank portions being enlarged providing a hollow tapering head with laterally-projecting shoulders on its under side.

105 In testimony whereof I affix my signature.

JAMES E. POTTER.
